My J. P. R. A. C. A.

UNITED STATES PATENT OFFICE.

ANTON GRAF, OF NEWBURYPORT, MASSACHUSETTS, ASSIGNOR OF ONE-HALF TO JOHN JOYCE, OF ANDOVER, MASSACHUSETTS.

HYDROMOTOR.

No. 894,135.

Specification of Letters Patent.

Patented July 21, 1908.

Application filed June 19, 1905, Serial No. 265,849. Renewed December 16, 1907. Serial No. 406,767.

To all whom it may concern:

Be it known that I, ANTON GRAF, of Newburyport, in the county of Essex and State of Massachusetts, have invented certain new and useful Improvements in Hydromotors, of which the following is a specification.

My invention relates to new and useful improvements in hydromotors, and for the purposes of illustration, the device is shown 10 in this application as embodied in a vessel for the propulsion thereof, although it is adapted to other uses as a motor.

The object of my invention is to produce a new and useful hydromotor simple in construction and efficient in operation.

My invention consists of certain novel features hereinafter described and particularly pointed out in the claims.

In the accompanying drawings which illustrate a construction embodying my invention, Figure 1 is a top plan view of a boat containing my improvements arranged in duplex. Fig. 2 is a detail side elevation of the hydromotor and coöperating parts, with 20 the arrows showing the direction of the flow of the water and with certain valves opened and others closed. Fig. 3 is a similar view to Fig. 2 and showing the position of the valves and the flow of the water indicated by 25 the arrows when the mechanism is operated to reverse the motion of the boat. Fig. 4 is a side view of the hydromotor.

Like letters of reference refer to like parts throughout the several views.

Within the boat A, shown in dotted lines, is located the boiler B of any suitable construction and from said boiler leads a steam pipe C controlled by the valve C' and forming an injector or inspirator C² within the 35 injector chamber D. To the bottom of the chamber D is connected a pipe E which is connected by a T-joint E⁵ to the pipe E' opening at E² to the water around the front of the boat. A hand-operated valve C' 40 controls the flow of steam to the injector C².

Connected to the chamber D is a pipe C³ which is bolted or otherwise secured to the duct F² of the hydromotor, which consists of two exterior plates F³ joined together by 45 suitable bolts as shown. Between the plates F³ are located a suitable drum mounted fast on the shaft f and having the plates f² f³ secured thereto and adapted to rotate therewith.

50 The construction of the hydromotor is not here given at length as the same will be found

described at large in my co-pending application filed April 2, 1906, Ser. No. 309,300.

The outlet f⁷ from the hydromotor (Figs. 3 and 4) connects with the pipe F⁴ which 60 communicates by a T-joint F⁸ with the exhaust pipe F⁵.

The pipe C³, between the injector chamber and the hydromotor, is connected by the T-joint C⁵ and the pipes D' and D² with the 65 exhaust pipe F⁵. In the pipe D' is the valve D⁹ to control the passage through the same.

The pipe E' is controlled by a suitable gate valve E³ which moves up and down, as hereinafter described. It is connected at its upper end by a slotted connection to the lever H² carried fast on the shaft H¹¹. On the said shaft supported by the brackets H H' is gear segment H⁵ which meshes with the rack H⁸ on the rod H⁴. This rod H⁴ extends rear- 70

wardly and is provided at its rear with a suitably mounted lever H⁹. On said rod H⁴ is mounted the bell crank J pivoted on to the standard J' and to said bell crank is connected a rod K moving in the guide J² on said 75 support J', and to said rod K is secured fast the rod K' likewise secured fast to the stem of the valve F' in the pipe C³. As shown in Fig. 2, the valves E³ and F' are raised thereby opening the pipes E' and C³. In the pipe F⁵ 80 which communicates with the pipe C³ through the connections previously described is a valve F⁶, the stem of which is connected to the lever H⁶ fast on the shaft H¹⁰ on which is also fixed fast another segment H⁵ which meshes with another rack H⁸ on the rod H⁴. As shown in Fig. 2 the valve 85 F⁶ is open, as are also the valves E³ and F'. The valve D⁹ in the pipe D' is closed.

Now with the parts described and in the 90 positions shown in Figs. 2 and 3, the boat is propelled forward by opening the valve C' which allows steam from the boiler B into the injector chamber D, which steam induces a suction of water from the front of the boat 100 through the pipe E' into the pipes E up into the injector chamber D through the pipe C³ past the valve F' which is open, into the duct F² and impacts against the blades f³ of the wheel, thereby rotating said wheel, and 105 passes out from the hydromotor through the outlet f⁷ into the pipe F⁴, then into the pipe F⁵, past the open valve F⁶, into the water at the rear of the boat, as indicated by arrows Fig. 2. In this arrangement it will be seen 110 the water is drawn by suction away from the front of the boat and forced out at the rear of

the boat, the action of which is to draw the boat ahead at the bow and force it ahead at the stern.

On the shafts *f* (see Fig. 1) are mounted 5 the bevel gears *a* which mesh with the bevel gears *b* on the shafts *c* supported by the brackets *d* and on the ends of said shafts are the propellers *e*. The rotation of the wheel within the plates *F*³ due to the impact of the 10 water and steam, causes a rotation of the shaft *f* which is communicated as above described to the propellers *e*.

To back the boat when standing still or to reverse the boat when going ahead, the operator takes hold of the lever *H*⁹ and pulls 15 the same rearward (see Fig. 3) which causes the rod *H*⁴ to move the gear segments *H*⁵ rearward, thereby opening the valve *E*⁴ connected to the lever *H*⁷ fast on the shaft *H*¹⁰ 20 and to close the valve *F*⁶ connected to the arm *H*⁶ fast on the shaft *H*¹¹, and to close the valve *F'* by means of the bell crank lever *J* and connections previously described, and further to close the valve *E*³ connected to the 25 lever *H*² fast on the shaft *H*¹¹ and to open the valve *G'* connected to the lever *H'* fast on said shaft *H*¹¹. The parts being moved as just described, and the valve *C'* being open, the injector *C*² induces suction of water from 30 the stern through the pipe *E*⁸ (Fig. 3) to the joint *E*⁵ and up through the pipe *E* into the injector chamber *D*, through the pipe *C*³ to the joint *C*⁵ (the valve *F'* being closed) down through the pipe *D'* (the valve *D*⁶ being 35 opened) to the pipe *D*² to the joint *F*⁸ (valve *F*⁶ being closed) up through the pipe *F*⁴ into the hydromotor, turning the wheel to the left and up and out through the duct *F*² to the joint *D*³ and down through the pipe *G*² 40 through the joint *D*⁴ and out through the pipe *G* discharging through the end *G*³ thereof in the front of the boat. This reversal of the propeller mechanism aided by the suction at the rear of the boat and the discharge 45 at the front of the boat moves the boat rearwardly. The course of the water and steam is indicated by the arrows in Fig. 3 in the backing or in reversing the boat for backward movement.

50 The valve *F'* controls the flow of steam pressure and water to the motor in that on the forward movement of the boat, said valve *F'* being open, steam pressure and water pass into the motor through the duct *F*² 55 from the pipe *C*³, while on the back or reverse movement of the boat, the valve *F'* being closed, steam pressure and water pass down the pipe *D'* into the pipe *D*² up through the pipe *F*⁴ into the motor out through the duct *F*² to the joint *D*³ and down through the pipe *G*² 60 and out through the pipe *G*.

While there is shown in Fig. 1 a hydromotor and its connecting ducts arranged in duplex, yet it will be understood that one hydromotor and its connecting ducts or any 65 number of motors and their connecting ducts may be used.

I do not limit myself to the arrangement and construction shown as the same may be varied without departing from the spirit of 70 my invention.

Having thus described the nature of my invention and set forth a construction embodying the same, what I claim as new and desire to secure by Letters Patent of the United 75 States is:

1. In apparatus of the character specified, a motor, a source of fluid under pressure having communications with opposite sides of said motor, a valve controlling each of said 80 communications, a liquid supply pipe leading to said source of fluid under pressure and provided with inlets opening in opposite directions, valves controlling said inlets, and an exhaust leading from said communications. 85

2. In apparatus of the character specified, a motor, a source of fluid under pressure having communications with opposite sides of said motor, a valve controlling each of said 90 communications, a liquid supply pipe leading to said source of fluid under pressure, exhaust pipes leading from said communications upon opposite sides of said motor and having outlets opening in opposite directions, and valves controlling said outlets. 95

3. In apparatus of the character specified, a motor, a source of fluid under pressure having communications with opposite sides of said motor, a valve controlling each of said 100 communications, a liquid supply pipe leading to said source of fluid under pressure and provided with inlets opening in opposite directions, valves controlling said inlets, exhaust pipes leading from said communications upon opposite sides of said motor and having 105 outlets opening in opposite directions, valves controlling said outlets, and means for operating all of said valves to open the circuit through the communication from the source of fluid under pressure, the liquid supply pipe 110 and the exhaust pipe on one side of the motor and closing the circuit on the other side of the motor.

In testimony whereof, I have signed my name to this specification in the presence of 115 two subscribing witnesses, this fourteenth day of June A. D. 1905.

ANTON GRAF.
